his Attorney.

UNITED STATES PATENT OFFICE.

HERBERT GRAY GIBBS, OF LONDON, ENGLAND.

KITE BALLOON.

Application filed December 17, 1924. Serial No. 756,379.

To all whom it may concern:

Be it known that I, HERBERT GRAY GIBBS, a subject of the King of Great Britain, residing at 19, Surrey Street, Strand, London, 5 W. C. 2, England, have invented certain new and useful Improvements in Kite Balloons, of which the following is a specification.

This invention relates to the construction 10 of kite balloons, of the type in which the balloon is permitted to expand or to contract as the volume of the gas increases or diminishes, owing to decrease or increase in atmospheric pressure or to changes in temperature of the gas.

According to this invention, the balloon is constructed in streamline form, and is of a capacity sufficient to contain the gas when expanded by diminution in atmospheric pressure to the capacity required for attaining great altitudes, say for instance 30,000 ft.

Longitudinally within the balloon four equi-distant rigging bands are attached to the fabric, the location of the two upper 25 rigging bands being equi-distant from a vertical plane passing through the longitudinal axis of the balloon, and the two lower rigging bands being also equi-distant from the same vertical plane.

The rigging band on the port side of the upper pair of rigging bands, is connected by elastic tension members with the rigging band on the starboard side of the lower pair of rigging bands; and the rigging band on 30 the starboard side of the upper pair of rigging bands is connected by a separate system of elastic tension members with the rigging band on the port side of the lower pair of rigging bands. The said elastic 35 tension members may be composed of india rubber, although they may if desired be constructed of steel springs; but india rubber elastic is preferable in most instances in order to facilitate packing of the kite balloon when deflated. The said elastic tension 40 members may be circular in cross section and spaced apart in the manner of lacing, the distance apart of each strand and the strength of such strands depending on the 45 strength of the elastic connections employed, and on the degree of pressure at which it is 50 desired to maintain the balloon.

In the drawings,

Fig. 1 is a perspective view partly in 55 section, showing the after part of a kite balloon with the interior rigging bands, the

elastic tension members being arranged diagonally across the balloon, and

Fig. 2 is a cross section of the same balloon.

Figs. 3 and 4 are detail views of the method of attachment of a rigging band to the interior of the balloon fabric, and

Fig. 5 is a further detail illustrating a convenient method of distributing the tension of the tension members onto the rigging band and thence to the balloon fabric.

Fig. 6 illustrates an alternative construction of elastic balloon constructed in accordance with this invention.

Referring particularly to Figs. 1, 2 and 6, A is the starboard upper rigging band, and B the port upper rigging band. C is the starboard lower rigging band, and D the port lower rigging band. E, E are the elastic members connecting the starboard upper rigging band A with the port lower rigging band D, and F, F are the elastic members connecting the port upper rigging band B with the starboard lower rigging band C.

As shown at Fig. 2, the tension members E and F have caused the rigging bands A and D to be drawn together and the rigging bands B and C also to be drawn together, to the extent at which the pressure of the gas balances the tension on the elastic members E and F, and in the dotted line around the full line section the balloon is shown to have expanded to a larger cubic capacity, either by reason of diminution of external atmospheric pressure due for instance to increasing altitude, or to expansion of the gas contained in the balloon due to increase in temperature. In such case the expansion of the balloon increases the tension on the elastic members E and F.

In the modification shown at Fig. 6, the rigging bands, instead of being placed equidistant circumferentially around the longitudinal axis of the balloon, are placed in 100 symmetrical positions but closer together in vertical directions and farther apart in horizontal directions than when they are equidistant circumferentially. This increases the surface of the balloon on the upper side and on the lower side where two large lobes are formed, and diminishes the surface of the portion of the balloon on the port and starboard sides where smaller lobes are formed. The effect of changing the proportion in this way is to lessen the liability of 105 the collection of snow or water in the longi-

tudinal folds of the balloon outside the location of the rigging bands A, B, C and D. The larger lobe on the under side of the balloon also facilitates the suitable attachment 5 of the patches to which the rigging G of the car suspension is attached.

The elastic tension members may completely traverse the balloon diagonally as before described, or they may be shortened 10 by the introduction of fabric gussets extending inwardly from the rigging bands.

At Figs. 3 and 4 a suitable method of attachment of the rigging band to the fabric of the balloon is shown. The band is 15 constructed of fabric doubled upon itself so as to leave two edges A¹, A² for attachment to the interior walls of the balloon, the folded portion A³ forming an inwardly extending pocket to receive wooden pegs 20 H for locking the ends of the elastic tension members E in position. This folded portion A³ may be extended whereby the shortening of the elastic tension members is facilitated.

25 Instead of, or in addition to an inwardly extended folded portion A³ of the rigging bands, non-elastic cords may be employed with the object of reducing the length of 30 the elastic tension members. The non-elastic cords may, for example, be attached to the rigging bands as shown at Fig. 5, where the elastic tension members E are attached to divide crows' feet E¹, E² which in their 35 turn are attached to eyelets E³ in the folded portion A³ of the rigging band.

The usual tail fins may be employed with 40 their centres at angles radiating 120° apart, and the said fins may be made to communicate with the interior of the balloon and 45 contain gas instead of air, which is the general practice. The inflation of the said fins with gas maintains their form, while the balloon is on the ground, and promotes stability when letting out and hauling down when the balloon is near the ground.

What I claim as my invention and desire to secure by Letters Patent is:—

1. An elastic kite balloon, in which the gas is maintained at the desired degree of pressure by means of tension members, four rigging bands on the interior of the balloon, two on the starboard side and two on the port side, elastic tension members connecting the upper starboard rigging band to the lower port rigging band, and elastic tension members connecting the upper port rigging band to the lower starboard rigging band. 50

10 2. An elastic kite balloon, in which the gas is maintained at the desired degree of pressure by means of tension members, four rigging bands spaced equi-distant apart on the interior of the balloon, two on the starboard side and two on the port side, elastic tension members connecting the upper starboard rigging band to the lower port rigging band, and elastic tension members connecting the upper port rigging band to the lower starboard rigging band. 55

15 3. An elastic kite balloon, in which the gas is maintained at the desired degree of pressure by means of tension members, four rigging bands on the interior of the balloon, two on the starboard side and two on the port side, the distance between the starboard rigging bands and the port rigging bands being greater than the distance of 20 upper and lower rigging bands in each pair from each other, elastic tension members connecting the upper starboard rigging band to the lower port rigging band, and elastic tension members connecting the upper port rigging band to the lower starboard rigging band. 75

25 In witness whereof I have hereunto set my hand in the presence of two witnesses.

HERBERT GRAY GIBBS.
